JOHN K. MILLER AND ALLEN O. MILLER, OF SEATTLE, WASHINGTON.

DRAFT APPARATUS.

1,035,988.

Specification of Letters Patent. Patented Aug. 20, 1912.

Application filed January 19, 1911. Serial No. 603,487.

To all whom it may concern:

Be it known that we, JOHN K. MILLER and ALLEN O. MILLER, citizens of the United States, residing at Seattle, in the county of King and State of Washington, have invented certain new and useful Improvements in Draft Apparatus, of which the following is a specification.

This invention relates to draft apparatus wherein the cinders and burning particles of matter drawn from a furnace through means of a forced or induced draft are first separated from the gaseous products of combustion and then withdrawn from the separator to be again delivered and utilized in the furnace. It more particularly relates to improvements on prior patent application Serial No. 581,112, filed Sept. 8, 1910.

The objects of said improvements are to admit sufficient atmospheric air to the return duct carrying the said unburned matter to the furnace to promote the combustion of the same and raise the general efficiency of the furnace by admitting the same in a blast at the approximate point of combustion in the fire box.

The invention consists in the novel arrangement and combination of devices, as will be hereinafter described and claimed.

Figure 1 is a view illustrating apparatus embodying our invention, partly in side elevation and partly in section, and, Fig. 2 is a horizontal sectional view of the separating chamber taken on the line 2—2 of Fig. 1, the smoke conduit being broken away.

The reference numeral 1 designates a smoke outlet of a boiler furnace 2 through which the draft is induced by means of a power-driven blower 3. The conduit 4, through which said smoke is driven, communicates tangentially with a separator 5 which centrifugally separates the heavier particles from the smoke. Such particles are gravitated toward the bottom 6 of said separator where they are influenced by a suction current and drawn into the tangentially disposed orifice 7 of a duct 8, which transports them through an auxiliary blower 9, and a duct 8' to an aperture 10 where the latter duct enters the fire-box and directs the issuing blast above the grate bars at approximately the point of combustion of the gaseous products resulting from the distillation of the wood-fuel.

It may be remarked that the devices here described are mainly employed, though not

exclusively, in power plants such as lumber manufactories where the refuse wood material is burned as fuel. Such material is of relatively low fuel value and usually contains a considerable amount of moisture. An induced or other forced draft is generally employed to effect the necessary combustion of such relatively inefficient fuel. Owing to the relatively high pressures ordinarily generated by the inducing blower, as 3, a considerable amount of such fuel is drawn through the flues in an unconsumed state in the form of cinders or unburned charcoal and ordinarily wasted. The escape of this carbonized fuel is a more serious loss than is usually considered as the same comprises a substantial proportion of the total amount of fuel deposited on the grates and a considerable absorption of heat has occurred in the drying of this fuel and the raising of the water vapor to the temperature of the combustion chamber. Such carbonized fuel is of high calorific value as it has been withdrawn from the fire-box when at about the point of combustion and, when reentered, is in a condition to be easily kindled.

Approved devices for effecting the saving of the unburned particles accompanying the flue gases are disclosed in our said prior patent application. A further improvement and advance is effected by the adaptation and arrangement of the discharge end 10 of said duct 8 in its entrance to the fire-box of the boiler furnace and provision for the admission of atmospheric air into said duct to supply oxygen to the fire-box under the most favorable conditions for combustion purposes. To that end, in the duct 8, 8', communicating with the cinder separator and the boiler furnace at either end, we form an opening 11 provided with an adjustable cover 12 through which air may be admitted in desired quantities to be admixed with the gases drawn with the cinders from the separator. Said opening is desirably made in the duct 8 at or near the inlet of same to the auxiliary fan 9 whereat the inrush of cooler gases serves to absorb a portion of the heat that may be generated in the blower-bearings. The high temperature of the gases as they are withdrawn from the separator at 7 in addition to the heat derived from said bearings raises the atmospheric air admitted to a temperature highly conducive to combustion.

The proportionate amount of oxygen dis-

coverable in the duct 8 before the admission of air is about 12 per cent. which, after such admission, is raised to an approximate 17.5 per cent.; a gas not greatly inferior to air for supplying oxygen. At the same relative positions carbon-dioxide is reduced from 7.8 per cent. to 2.3 per cent. These gases with their accompanying carbonized particles and in heated condition are introduced violently into the furnace through the connection 10 and directed by an interior nozzle (not shown) at a point where they may be most efficiently combined with the fresh gaseous distillations of the fuel and promote the general combustion. Such point will usually be at or near the bridge wall of the furnace.

An analysis of the resultant gaseous products will disclose that approximately the equivalent of the oxygen admitted with the atmospheric air to the mixture has been utilized in combustion. Practical tests also show that a greatly increased efficiency has been effected owing to the decrease of the total amount of air admitted to the fire-box. This decrease occurs in the air drawn through the grates and consequently reduces the amount of air requiring to be raised to a relatively high temperature before being available for combustion. Any excess of air over the amount required for good combustion is disadvantageous as it but absorbs considerable amounts of sensible heat which escapes with the flue gas. In the present method a considerable proportion of such unchanged air is returned to the fire-box with the accompanying cinders and in condition to combine readily with the gaseous distillations there encountered.

It may be stated that a considerable saving in power is effected in operating under the improved conditions described. Smaller quantities of flue gases are handled, a considerably reduced amount of air is drawn through the grates, therefore sufficient working pressures may be maintained within the flues although the speed of the blower be substantially reduced.

What we claim, is—

1. An apparatus for inducing furnace drafts comprising the combination with a furnace provided with an outlet for the products of combustion, of a blower with which said outlet solely communicates, a separator, means for discharging gases from the blower tangentially into the separator to separate the solid matter therefrom, a smoke stack depending into said separator, said separator having a closed bottom, a pipe communicating with said separator at the bottom thereof, a suction device in which said pipe opens, and a conducting pipe leading from said suction device to said furnace above the grate bars thereof.

2. An apparatus for inducing furnace

drafts comprising the combination with a furnace provided with an outlet for the products of combustion, of a blower with which said outlet solely communicates, a separator, means for discharging gases from the blower tangentially into the separator to separate the solid matter therefrom, a smoke stack depending into said separator, said separator having a closed bottom, a pipe communicating with said separator at the bottom thereof, a suction device in which said pipe opens, a conducting pipe leading from said suction device to said furnace above the grate bars thereof, and regulatable means for admitting air to said suction device.

3. An apparatus for the purpose set forth comprising the combination with a furnace, of a blower, an outlet pipe for the products of combustion from said furnace, said outlet pipe communicating solely with said blower, a separator having a funnel-shaped closed lower end, means for establishing communication between the blower and the upper portion of said separator for discharging the gases tangentially in the latter to separate the solid matter from the gases, a smoke stack supported by and extending in said separator, a suction device, means for establishing communication between the bottom of the separator and said suction device, and means for establishing communication between said suction device and the furnace above the grate bars thereof.

4. An apparatus for the purpose set forth comprising the combination with a furnace, of a blower, an outlet pipe for the products of combustion from said furnace, said outlet pipe communicating solely with said blower, a separator having a funnel-shaped closed lower end, means for establishing communication between the blower and the upper portion of said separator for discharging the gases tangentially in the latter to separate the solid matter from the gases, a smoke stack supported by and extending in said separator, a suction device, means for establishing communication between the bottom of the separator and said suction device, means for establishing communication between said suction device and the furnace above the grate bars thereof, and a regulatable means for admitting air to said suction device.

5. An apparatus for the purpose set forth, comprising the combination with a furnace, of an outlet for the products of combustion from the furnace, means for separating the solid particles from the products of combustion, said outlet communicating solely with said means and discharging the gases tangentially into said separating means, a receptacle for receiving said separated particles, a suction device, means for establishing communication between

said suction device and said receptacle, means for establishing communication between said suction device and the furnace above the grate bars thereof, and a smoke 5 stack communicating with and supported by said separating means.

6. An apparatus for the purpose set forth, comprising the combination with a furnace, of an outlet for the products of combustion 10 from the furnace, means for separating the solid particles from the products of combustion, said outlet communicating solely with said means and discharging the gases tangentially into said separating means, a receptacle for receiving said separated parti- 15

cles, a suction device, means for establishing communication between said suction device and said receptacle, means for establishing communication between said suction device and the furnace above the grate bars 20 thereof, a smoke stack communicating with and supported by said separating means, and regulatable means for admitting air to said suction device.
